UNITED STATES PATENT OFFICE.

ALFRED K. PEHRSON, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

ARTICULATED CAR.

Application filed November 13, 1925. Serial No. 68,802.

To all whom it may concern:

Be it known that I, ALFRED K. PEHRSON, a subject of the King of Sweden, residing in Bellevue, in the county of Allegheny and State of Pennsylvania, have invented certain new and useful Improvements in Articulated Cars, of which the following is a specification.

This invention relates to articulated cars each of which comprises a plurality of car bodies and has for an object the provision of a vestibule member between the adjacent ends of two of the bodies which is operable by the bodies for maintaining the proper relationship between said bodies and member at all times.

Another object of the invention is to provide means whereby the vestibule member, between the adjacent ends of two adjacent bodies of an articulated car, is automatically movable or adjustable by the movement of the bodies relative to each other.

Another object of the invention is to provide means whereby the vestibule member, which is movably mounted between the adjacent ends of two adjacent bodies of an articulated car, will cooperate with said bodies in such a manner that the transverse center line of the vestibule member will bisect any angle formed by the longitudinal center lines of the adjacent bodies.

Another object of the invention is to provide the adjacent ends of the adjacent bodies of an articulated car with means for driving or adjusting the vestibule member, arranged between said ends, to its proper position relative to said bodies, so that the passage-way through the car will be unobstructed at all times.

A further object of the invention is the provision of means whereby the vestibule member, between the adjacent ends of two adjacent bodies of an articulated car, is supported by one of the bodies.

Referring to the drawings in which like reference characters refer to like parts, Fig. 1 is a sectional plan view of the adjacent ends of two adjacent car bodies and vestibule member of an articulated car embodying the invention; Fig. 2 is an enlarged cross sectional view taken on the line 2-2 of Fig. 1; Fig. 3 is an enlarged longitudinal sectional view taken on the line 3-3 of Fig. 1; Fig. 4 is an enlarged sectional view

taken on the line 4-4 of Fig. 1; Fig. 5 is a diagrammatic plan view of a portion of the car showing the positions of the adjacent end portions of two adjacent bodies and the vestibule member and mechanism when these bodies are on a portion of straight track; Fig. 6 is a like view showing one of the bodies on straight portion of the track and the other on a curved portion of the track and Fig. 7 is a like view showing both of the bodies on a curved portion of the track.

Referring now in detail to the drawings, the reference character 1 indicates an articulated car which comprises a plurality of bodies 2, the adjacent ends of which are pivotally supported upon a truck (not shown) of any suitable construction. In the present embodiment of the invention the truck bolster 4 is provided with a truck center bearing member 5 in which the body center bearing members 6 of the adjacent ends of the underframes of two adjacent bodies are adapted to extend and cooperate with to form a bearing for the bodies and for maintaining said bodies in their proper spaced relation against longitudinal movement in one direction, there being a spherical member 7 mounted in the underframes above the center bearing which prevents relative movement of the bodies in the opposite direction and also prevents one underframe from moving vertically relative to the other.

The foregoing construction has been described in detail in an application for U. S. Letters Patent filed February 14, 1925 in my name for connection for articulated cars and serially numbered 9190. It will be understood that while only one center bearing arrangement has been described, the present invention can be used in conjunction with car bodies which are supported up on a truck by any other suitable bearing arrangement.

Between the adjacent ends of two bodies a vestibule member 8 is provided which comprises a bottom 9, sides 10 and a top or roof portion (not shown). The construction of this member 8, its application to the adjacent ends of two bodies as well as the weatherproofing means between the member and the bodies have been fully described in a pending application for U. S. Letters Patent filed September 1, 1925, in my name and Karl O. Winell, jointly, for articulated

car, and serially numbered 53793. The bottom 9 of this member has secured to its underside a center bearing member 12 which seats in and cooperates with a center bearing member 13 secured to or formed integral with the end portion of one of the underframes.

At each side of the longitudinal center line of the car, a pair of links 14 are provided the adjacent ends of which are pivotally connected to a projection 15 formed on a slide member 16. These links when so connected extend between the adjacent ends of adjacent cars and their outer ends are pivotally connected with the underframes through the medium of bolts 17 or any other suitable means.

Secured to the underside of the bottom 9 of the vestibule member 8 there are members 18 each of which is located at the transverse center line of the vestibule member at one side of the longitudinal center line of the car and vestibule member. Each member is provided with a groove or way 19 which is preferably of T shape and is adapted to receive the upper portion or head 20 of the member 16 in such a manner that the member 16 is freely slidable in the slot 19. It will here be noted that as the adjacent bodies of the car assume an angle to each other, the links 14, due to their connections with the bodies and their sliding connection with the vestibule member, will cause the vestibule member to rotate to such an extent that the transverse center line of the vestibule member will bisect any angle formed by the longitudinal center lines of the bodies.

When the car is on straight track, the vestibule member 8 will be maintained by the links 14 in such a position that the transverse center line A thereof will be at right angles to the longitudinal center lines B of the bodies as shown in Fig. 5 of the drawings. As one body of the car moves from a straight portion of the track to a curved portion the links 14 and vestibule 8 will move to the positions as shown in Fig. 6 in which position the transverse center line A of the vestibule member will bisect the angle formed by the longitudinal center lines B of the adjacent bodies. When two adjacent bodies are on a portion of curved track the links 14 and vestibule 8 are in the positions as shown in Fig. 7 and the transverse center line of the vestibule member will bisect the angle formed by the longitudinal center lines B of the bodies. The vestibule member is maintained in one of the positions shown in Figs. 5, 6 or 7 or any other position by the links 14, until such time as the relative positions of the bodies are changed from any of the positions just referred to.

It will be understood that many changes

may be made in the device without departing from the spirit and scope of the invention as defined in the appended claims.

Having thus described the invention, what I claim as new and desire to secure by Letters Patent is:—

1. In an articulated car, a plurality of bodies, a vestibule member loosely mounted between the adjacent ends of two of said bodies, and means operable by said ends for maintaining the relationship between said bodies and vestibule member that the transverse center line of the vestibule member will bisect any angle formed by the longitudinal center line of said bodies. 80

2. An articulated car comprising a plurality of bodies, a vestibule member mounted between the adjacent ends of two of said bodies, and means operable by said bodies for maintaining the proper relationship of said vestibule member with said bodies. 85

3. An articulated car comprising a plurality of bodies, a vestibule member mounted between the adjacent ends of two of said bodies, and means connected with said bodies and vestibule member for maintaining the proper relationship of said vestibule member with said bodies. 90

4. In an articulated car, a plurality of bodies, a vestibule member between adjacent bodies, and means operable by said adjacent bodies for maintaining said vestibule member in its proper relation to said bodies. 95

5. An articulated car comprising a plurality of bodies, a vestibule member between the adjacent ends of two of said bodies, and carried by one of said bodies, and connections from each of said ends to said vestibule member for adjusting said vestibule member to its proper position relative to said bodies. 100

6. An articulated car comprising a plurality of car bodies, a vestibule member mounted on the end of one of said bodies and adapted to cooperate with the adjacent end of an adjacent body, and means on both of said ends for driving said vestibule member. 110

7. In an articulated car, a vestibule member between the adjacent ends of two adjacent bodies of said car, and means connected with said bodies for moving said vestibule member. 115

8. In an articulated car, a vestibule member between the adjacent ends of two adjacent bodies of said car, and means extending between said bodies for moving said member. 120

9. A car comprising a plurality of connected car bodies, a vestibule member between the adjacent ends of two of said bodies, and connections from said ends to said member for moving said member when said bodies move at an angle to each other. 125

10. An articulated car comprising a plurality of bodies, a vestibule member between the adjacent ends of two of said bodies, a movable member on said vestibule member, and a link mounted on each of said bodies and pivotally connected with said movable member.
11. An articulated car comprising a plurality of bodies, a vestibule member rotatably mounted between the adjacent ends of two of said bodies, and means mounted on said bodies and connected with said member for rotating said member.
12. An articulated car comprising a plurality of bodies, a vestibule member rotatably mounted between the adjacent ends of two of said bodies, and link means mounted on said bodies and connected with said member for rotating said member.
13. An articulated car comprising a plurality of bodies, a rotatable vestibule member between the adjacent ends of two of said bodies and means operable by said ends for rotating said member.
14. An articulated car comprising a plurality of bodies, a vestibule member between the adjacent ends of two of said bodies, a member slidably connected with said vestibule member, and links connecting said bodies and slidable member.
15. An articulated car comprising a plurality of bodies, a vestibule member for the adjacent ends of two of said bodies, a connection extending between and connected with said ends, a joint in said connection intermediate its ends, and a member forming a portion of said joint movably connected with said vestibule member.
16. An articulated car comprising a plurality of bodies, a vestibule member for the adjacent ends of two of said bodies, a slide member mounted on said vestibule member, and link means connecting said slide member with said ends.
17. In an articulated car, a plurality of car bodies, and a single vestibule member mounted on the end of one of said bodies, and adapted to cooperate with the adjacent end of an adjacent body.
18. In an articulated car, a plurality of car bodies, a vestibule member for the adjacent ends of two of said bodies, and a support for said member on one of said bodies, said member defining a passageway between said ends.
19. The combination with the adjacent ends of two adjacent bodies of an articulated car, a vestibule member for said bodies movable relative to said ends, and a support for said member on one of said bodies, said member defining a passageway between said bodies.
20. An articulated car comprising a plurality of car bodies, a vestibule member mounted on the end of one of said bodies and adapted to cooperate with the adjacent end of an adjacent body, and means operable by said ends for moving said vestibule member.
21. An articulated car comprising a plurality of car bodies, a vestibule member rotatably mounted on the end of one of said bodies and adapted to cooperate with the adjacent end of an adjacent body and means operable by both of said bodies for rotating said vestibule member.
22. An articulated car comprising a plurality of car bodies, a vestibule member mounted on the end of one of said bodies, and adapted to cooperate with the adjacent end of an adjacent body, said member being capable of rotary movement relative to both of said ends, and means associated with said ends for controlling the movement of said vestibule member.
23. In an articulated car, a plurality of bodies, a vestibule member between the adjacent ends of two of said bodies, said member being capable of limited rotary movement, and means operable by said bodies for controlling the movement of said member.
24. In an articulated car, a plurality of bodies, a vestibule member movably mounted between the adjacent ends of two of said bodies, and means connected with said bodies and said member for moving said member so that the angular movement of said member is less than the angular movement between said bodies.
25. In an articulated car, a plurality of bodies, a vestibule member rotatably mounted between the adjacent ends of two of said bodies, and means connected with said bodies and said member for moving said member so that the rotary movement of said member is less than that which would be caused by the angular movement between said bodies.
26. In an articulated car, a plurality of bodies, a vestibule member rotatably mounted between the adjacent ends of two of said bodies, and means connected with said bodies and said member for moving said member so that the movement of said vestibule member is less than the movement of said bodies relative to each other.
27. The combination with the adjacent ends of adjacent bodies of an articulated car, of an extension on one of said ends, and a vestibule member for both of said ends mounted on said extension.
28. The combination with the adjacent ends of adjacent bodies of an articulated car, of an extension on one of said ends, and a vestibule member loosely mounted on said extension, said member defining a passageway between said ends.

In testimony whereof I affix my signature.

ALFRED K. PEHRSON.
